F. D. HALL

REPRODUCING NEEDLE FOR TALKING MACHINES

Filed March 4, 1922.

Witness:

F. D. Hall

Inventor
Frederick D. Hall,
By A. M. Belfield, Atty.

UNITED STATES PATENT OFFICE.

FREDERICK D. HALL, OF CHICAGO, ILLINOIS, ASSIGNOR TO HALL MFG. CO., OF CHICAGO, ILLINOIS, A CORPORATION OF ILLINOIS.

REPRODUCING NEEDLE FOR TALKING MACHINES.

Application filed March 4, 1922. Serial No. 541,019.

To all whom it may concern:

Be it known that I, FREDERICK D. HALL, a citizen of the United States, residing at Chicago, in the county of Cook and State of Illinois, have invented a certain new and useful Improvement in Reproducing Needles for Talking Machines, of which the following is a full, clear, concise, and exact description, reference being had to the accompanying drawings, forming a part of this specification.

My invention relates to reproducing needles for talking machines, phonographs and similar instruments.

One of the objects of the invention is to provide a practical and efficient form of needle of the class specified.

Another object of the invention is to secure a high degree of excellence in the combined action of needle and record.

Another object of the invention is to secure accuracy of rendition and fine tone quality.

Another object of the invention is to prolong the effective life of the needle.

Another object of the invention is to arrange for the economic and advantageous manufacture of the needles in quantity.

In the accompanying drawings Fig. 1 is a side elevation of a needle embodying my present invention;

Fig. 2 is a perspective view of the same on an enlarged scale;

Fig. 3 is an end view on a still larger scale;

Fig. 4 is a side view on the same scale as Fig. 3; and

Fig. 5 is an end view of a modified form of construction.

Referring to the drawings, I show a needle indicated as A adapted for use for talking machines, phonographs and similar machines.

The needle shown is preferably made of fiber, such as bamboo, or other vegetable matter, although other materials could be used. When made of bamboo or other fiber, the grain of the fiber preferably runs lengthwise of the needle.

The needle is preferably of a general triangular cross section, having longitudinal sides 1, 2 and 3, as best shown in Figs. 2 and

3, the side 1 being the outer surface of the bamboo material, having an outer skin or cortex 1^a. One end is cut to form an inclined or sloping surface 4, which produces a point 5 at its junction with the corner or edge 6 between sides 1 and 3. The surface 4 also preferably slopes or inclines slightly away from side 1 to make a sharper edge 60 and point, as shown in Fig. 4.

In accordance with my present invention at least one of the sides 2 or 3 is longitudinally scooped or hollowed out. In Figs. 1 to 4, inclusive, both sides 2 and 3 are scooped or hollowed out; in Fig. 5 only side 3^a, side 2^a being flat. By such arrangement, the point 5 will be sharper and longer, due to the concavity of sides 3 and 3^a. Thus better action of needle or record is secured, better tone quality, greater accuracy, and longer effective life of needle.

The arrangement of Figs. 1 to 4, with both the sides 2 and 3 hollowed or scooped out, is preferred, as this is advantageous from a manufacturing standpoint. By such arrangement, the point 5 may be formed at the junction of sides 1 and 3, or 1 and 2, and so it is unnecessary in cutting the points 5, to discriminate between sides 2 and 3, and the needles may be fed and cut accordingly. In the arrangement of Fig. 5, point 5 must be formed at junction of sides 1 and 3^a, and consequently needles must be cut accordingly and time would be taken by operator to examine and position needle properly.

It will be understood that changes and modifications may be made without departing from the spirit of the invention.

What I claim is:

1. A needle of the class specified comprising a strip having a point formed at the junction of two angularly disposed longitudinally extending meeting sides, one of which is longitudinally scooped or hollowed.

2. A needle of the class specified comprising a strip having a point formed at the junction of two angularly disposed longitudinally extending meeting sides, one of which is longitudinally scooped or hollowed and the other of which is plane.

3. A needle of the class specified comprising a strip of bamboo material provided with two angularly disposed longitudinally

extending meeting sides one of which has a skin or case provided by the outside of the bamboo material and the other of which is longitudinally scooped or hollowed.

5 4. A needle of the class specified comprising a strip of bamboo material of general triangular cross section, one of said sides be-

ing the outer side of the bamboo material and the other two sides being longitudinally scooped or hollowed. 10

In witness whereof, I hereunto subscribe my name this 2nd day of February, A. D., 1922.

FREDERICK D. HALL.
